UNITED STATES PATENT OFFICE

FRANCIS J. PLYM, OF NILES, MICHIGAN, ASSIGNOR TO THE KAWNEER COMPANY, OF NILES, MICHIGAN, A CORPORATION OF MICHIGAN

STORE FRONT CONSTRUCTION

Application filed May 11, 1929. Serial No. 362,365.

This invention relates to store front constructions and more in particular to a novel sash construction in which the glass is firmly, yet yieldably held in position.

5 Among the objects of my invention are to provide a sash construction which may be readily assembled, the face plate or moulding being readily shifted and adjusted without the necessity of matching screw holes, thus 10 saving considerable time in the setting of the sash.

A further object is to provide a novel sash construction in which the sash is located entirely above the flooring board, the whole 15 adjustment being above such flooring and by a direct friction pull.

A still further object is to provide a novel construction of inner or pane seating section provided with an integral gutter. Another 20 object of the invention is to provide a pair of resilient sash members operatively held in position and adjusted by means of a helical grooved member.

Other objects are to provide a construction 25 of maximum simplicity, efficiency, economy, and ease of assembly and operation, and such further objects, advantages, and capabilities as will later more fully appear and are inherently possessed thereby.

30 My invention further resides in the combination, construction and arrangement of parts illustrated in the accompanying drawings, and while I have shown therein a preferred embodiment, I desire it to be understood that the same is susceptible of modification and change, without departing from the spirit of my invention.

In the drawings:

40 Fig. 1 is a view in front elevation of a window provided with the novel sash construction.

Fig. 2 is a view in vertical cross section taken on the line 2—2 of Fig. 1.

45 Fig. 3 is a view in vertical cross section taken on the line 3—3 of Fig. 1, and showing more clearly the means of draining the inside of the sash construction.

Fig. 4 is a fragmentary view in rear elevation of the sash construction, a portion of

the gutter being broken away to more clearly disclose the details.

Fig. 5 is a fragmentary view in front elevation of the sash construction, a portion of the face plate or moulding being broken away to more clearly disclose the construction of the attaching means. 55

Fig. 6 is a view in perspective of the inner and outer sash members.

Fig. 7 is a view in horizontal cross section 60 taken on the line 7—7 of Fig. 1.

Referring more particularly to the disclosure in the drawings, my novel sash construction is shown as mounted upon a window frame comprising a head jamb A, side 65 jambs B and a sill C. The sash construction 1 comprises an inner sash member or pane seating section 2 provided with a base 3 having a doubled-back flange or projection 4 forming a gutter between the same and a 70 backing member 5, said backing member being bent to form a glass supporting member or shelf 6. The rear sash member or pane seating section is anchored to the sill or 75 flooring by means of screws or the like 7. 75 Suitable spaced in the backing member are openings 8 for the reception of helical screws or securing means 9.

The helical screws or grooved members 9 are shown as provided with a slotted head 80 10, shoulder 11, cylindrical shank 12 provided with a tit or tapered projection 13 and helical threads 14. These threads are shown as suitably spaced on the shank and of substantially equal diameter. 85

The screw threads of the screw member 9 are adapted to draw inwardly and adjustably position a moulding, face plate or outer sash member 15 having a glass engaging portion or flange 16 and base 17, provided at 90 its inner end with an upturned and longitudinally extending flange 18, this flange or rib being adapted to be engaged by the spaced threads 14 of the helical screw members. The tit or tapered projection 13 of the screw members will ride over the edge of the rib or flange 18 and allow for engagement of the threads with the rib or flange, the threads being suitably spaced so that the grooves therebetween are of a size sufficient to inter- 95 100

cept and hold the rib or flange. The threads of the screw member, being of substantially equal diameter, contact with the base of the moulding or outer sash member, and also with the bottom of the shelf or supporting member 6 of the inner sash member or pane seating section. Thus these threads will suitably brace the shelf or glass supporting member, and prevent any tipping or canting of both the face plate or moulding, and the shelf or glass supporting member. Also the shoulder 11 of the screw member is so constructed as to fit snugly within the opening 8 of the backing member, thus preventing any tipping or canting of the screw, due to vibration or other causes. The shelf prevents contact of the screws with the edges of the glass.

My novel construction of helical or worm screw, and the construction of the inner and outer sash members, eliminates all matching of screw holes in these sash members, and thus these members may be shifted, as desired. Especially is this true with the outer sash member, which need not, by reason of my construction, be standardized or matched with the rear pane seating member.

In the assembly of this sash construction, the rear sash member or pane seating section is first placed in position, and attached to the sill or flooring, by means of screws or the like 7, which are placed in the gutter. The glass is then placed in position upon a plurality of suitably spaced leather blocks 19. The outer sash member or moulding is next placed against the glass, the inner end of the base of the moulding or face plate seating on the base 3 of the inner pane seating or sash member 2. The screws 9 are then screwed home, the tip or 40 tapered projection 13 thereof riding over the flange 18 of the face plate or outer moulding, and the threads thereof engaging this flange, thus drawing the flange and face plate or moulding inwardly or rearwardly, the whole 45 adjustment being above the flooring. It is to be noted that the sash construction on the side and head jambs, as shown more clearly in Fig. 7, is not provided with the longitudinally extending flange or rib 4, since no gutter 50 construction is here necessary.

In order to provide proper ventilation and drainage for the sash construction, the inner sash member or pane seating section is provided with suitably spaced drain holes 20 and 55 21, while the outer sash member or face moulding is provided with drain holes 22. Proper ventilation and drainage are necessary in all sash constructions in order to avoid too great, or unequal expansion or contraction of 60 the glass, and to drain away any condensate or water which may collect in the sash construction.

The novel construction of screw or helically grooved member, allows for a ready assembly, adjustment or replacement of a pane

of glass, or of either or both of the sash members. A slight turn of the head of this member by means of a screw driver or the like, will draw the sash members into contacting and holding engagement with a pane of glass, 70 and although I have shown this member as applied to a sash construction, it will be readily seen and understood that the same is adapted for a plurality of uses and in various constructions.

As clearly disclosed in the drawings, my novel sash construction embodies a minimum number of parts which are adapted to firmly seat the glass, but yieldably hold the same in position, and at the same time allow for the 80 ready removal or replacement of the glass. The invention sets forth and possesses to the fullest degree, all the characteristics of ventilation, drainage, elasticity and ease of setting which are essential to an efficient sash 85 construction.

Having thus disclosed my invention, I claim:

1. In a store front construction, a pane seating section comprising a sheet of metal bent upon itself to form a support for a pane of glass, a backing member for bearing against said pane, and a base having an up-standing rib for providing a gutter between said rib and backing member; a moulding, 95 and readily adjustable means in the pane seating section for drawing said moulding into contacting engagement with said pane, said adjustable means bearing against the support for additionally supporting the 100 same.

2. In a store front construction, a pane seating section comprising a sheet of metal bent upon itself to form a support for a pane of glass, a backing member for bearing 105 against said pane, and a base having an up-standing rib for providing a gutter between said rib and backing member; a moulding, and a screw member for drawing said moulding into contacting engagement with said 110 pane, said screw member being adapted to bear against said support for preventing collapse thereof.

3. In a store front construction, the combination of a pane seating section adapted 115 to be attached to a window sill or frame and formed with a gutter, a moulding provided with a longitudinal rib, means in said section adapted to engage said rib for drawing said moulding into yieldable contacting engagement with a pane of glass, and means in said gutter for anchoring said section on said window sill or frame.

4. In a store front construction, a pane seating section comprising a sheet of metal 125 bent upon itself to form a support for a pane of glass, a backing member for bearing against said pane, and a base having an up-standing rib for providing a gutter between said rib and backing member; a curved mould-

- ing having the base thereof bearing upon said section and the top adapted to contact with said pane, and a threaded member on said pane seating section and adapted to engage 5 a portion of said moulding for drawing the top of the moulding into contacting engagement with said pane, said threaded member being adapted to bear against said support for preventing collapse thereof.
- 10 5. In a store front construction, a pane seating section comprising a sheet of metal bent upon itself to form a support for a pane of glass, a backing member for bearing against said pane, and a base having an up- 15 standing rib for providing a gutter between said rib and backing member; means in said gutter for anchoring said section to a window sill or frame, a moulding, a rib on said moulding, and a screw member in said pane seating section and adapted to engage the rib on said moulding for drawing said moulding into yeildable contacting engagement with said pane.
6. In a store front construction, a pane 20 seating section comprising a sheet of metal bent upon itself to form a support for a pane of glass, a backing member for bearing against said pane, and a base having an up- 25 standing rib for providing a gutter between said rib and backing member; means in said gutter for anchoring said section to a window sill or frame, a moulding, a rib on said moulding, and a screw member in said pane seating section, said member being provided 30 with spaced threads adapted to intercept the rib on said moulding between adjacent threads for drawing said moulding into yeildable contacting engagement with said pane.
- 40 7. In a store front construction, a pane seating section comprising a sheet of metal bent upon itself to form a support for a pane of glass, a backing member for bearing against said pane, and a base having an up- 45 standing rib for providing a gutter between said rib and backing member; means in said gutter for anchoring said section to a window sill or frame, a moulding, a rib on said moulding, and a screw member in said pane seating section, said member being provided 50 with spaced threads and a tapered tip portion, the tip portion riding over the rib on said moulding and guiding the spaced threads into engagement with said rib for 55 intercepting the same between adjacent threads whereby said moulding is drawn into yeildable contacting engagement with the pane of glass.
8. In a store front construction, a pane 60 seating section comprising a sheet of metal bent upon itself to form a support for a pane of glass, a backing member for bearing against said pane, and a base having an up- 65 standing rib for providing a gutter between said rib and backing member; means in said
- gutter for anchoring said section to a window sill or frame, a moulding, a rib on said moulding, and a screw member in said pane seating section, said member being provided with spaced threads of substantially equal 70 diameter, said threads being adapted to intercept the rib on said moulding between adjacent threads for drawing said moulding into yeildable contacting engagement with said pane, and said threads further engaging 75 said moulding and support for preventing collapse of said support.
9. In a store front construction, a pane seating section comprising a sheet of metal bent upon itself to form a support for a pane 80 of glass, a backing member for bearing against said pane, and a base adapted to be mounted on a window sill or frame and having an upstanding flange or rib for providing a gutter between said flange or rib and 85 said backing member; a moulding provided with an upper glass holding portion, a base adapted to seat on the base of said pane seating section, and an upwardly extending rib; and a screw member in said pane seating sec- 90 tion for engaging said rib and drawing said moulding into yeildable contacting engagement with said pane of glass, said screw contacting said support and base of said moulding for additionally supporting and prevent- 95 ing collapse of said support.
10. In a store front construction, a pane seating section comprising a sheet of metal bent upon itself to form a support for a pane of glass, a backing member for bearing 100 against said pane, and a base provided with attaching means located rearwardly of said support; a moulding, and means for drawing said moulding into contacting engagement with said pane, said means bearing against 105 the support for preventing collapse thereof.
11. In a store front construction, a pane seating section comprising a sheet of metal bent upon itself to form a support for a pane of glass, a backing member for bearing 110 against said pane, and a base provided with a rearwardly extending portion; a moulding, and readily adjustable means in the pane seating section for drawing said moulding into contacting engagement with said pane, 115 said means bearing against the support for preventing collapse thereof.
12. In a store front construction, a pane seating section comprising a sheet of metal bent upon itself to form a support for a pane of glass, a backing member for bearing 120 against said pane, and a base having an upstanding rib providing a gutter between said rib and backing member; a moulding, and means for drawing said moulding into 125 contacting engagement with said pane, said means being adapted to bear against the support for preventing collapse thereof.
13. In a store front construction, the combination of a pane seating section having a 130

gutter and provided with a supporting member for a pane of glass, a moulding, and adjustable means in said section adapted to engage a portion of said moulding for drawing said moulding into yieldable contacting engagement with said pane of glass, said means bearing against said support for preventing collapse thereof.

14. In a store front construction, the combination of a pane seating section having a gutter and provided with a supporting member for a pane of glass, a moulding, and a screw member adapted to engage a portion of said moulding for drawing said moulding into yieldable contacting engagement with said pane of glass, said screw member bearing against said support for preventing collapse thereof.

In witness whereof, I hereunto subscribe my name to this specification.

FRANCIS J. PLYM.
